(57) **CLAIM**

I claim the ornamental design for a letter resealer, as shown and described.

DESCRIPTION

FIG. 1 is a perspective view of letter resealer showing my new design.

FIG. 2 is a top plan view thereof.

FIG. 3 is a bottom plan view thereof.

FIG. 4 is a right side elevation view thereof.

FIG. 5 is a left side elevation view thereof.

FIG. 6 is a front elevation view thereof.

FIG. 7 is a rear elevation view thereof.

FIG. 8 is a perspective view of letter resealer showing my new design.

FIG. 9 is a top plan view thereof.

FIG. 10 is a bottom plan view thereof.

FIG. 11 is a right side elevation view thereof.

FIG. 12 is a left side elevation view thereof.

FIG. 13 is a front elevation view thereof; and,

FIG. 14 is a rear elevation view thereof.

Broken lines in the drawings represent unclaimed environmental subject matter and form no part of the claimed design.
